United States Patent Office.

THOMAS E. PURCHASE, OF READING, PENNSYLVANIA, ASSIGNOR TO HIMSELF AND SAMUEL T. HODGKINS, OF SAME PLACE.

Letters Patent No. 101,658, dated April 5, 1870.

IMPROVEMENT IN PUDDLING AND OTHER FURNACES.

The Schedule referred to in these Letters Patent and making part of the same.

I, THOMAS E. PURCHASE, of Reading, county of Berks, State of Pennsylvania, have invented an Improvement in Furnaces, of which the following is a specification.

Nature and Object of the Invention.

My invention consists of a furnace, the exterior plating of which is composed of a series of hollow boxes, fitted together substantially as described hereafter, and communicating with each other through connecting pipes, and with supply and discharge-pipes, by which a constant circulation of water is maintained through the said boxes, the latter being thereby prevented from cracking and warping, the integrity of the furnace being preserved, and its exterior maintained in such a cool state that the attendants are freed from the excessive heat radiated from ordinary furnaces.

My invention further consists of a hollow fire-box, constructed and adapted to the fire-place of the furnace, as described hereafter, in order to preserve that part of the furnace containing the fuel.

My invention also consists of a peculiar metal bridge, for supporting the bed of the furnace, also of certain detachable strips, for guiding the door of the furnace, the said strips being removed when a larger door is required.

Description of the Accompanying Drawing.

Figure 1 is a plan view, illustrating my invention as applied to a puddling furnace;

Figure 2, a sectional elevation on the line 1-2, fig. 1;

Figure 3, a side view;

Figure 4, a transverse vertical section on the line 3-4, fig. 3; and

Figure 5, a detached view of part of the fire-box.

General Description

As regards external form, my improved furnace is similar to those in common use for puddling purposes, the fire-place A being at one end, the central portion, containing the puddling-chamber, being somewhat wider than the fire-place, and the rear of the furnace being contracted in the usual manner. It should be understood that the fire-brick lining of the furnace is omitted, for the better illustration of my invention.

The outer plating of the furnace, instead of consisting of the usual solid sheets of cast-iron, is composed of a series of hollow cast-iron boxes or sections, B, snugly fitted together at the edges, as shown in fig. 1, each box having, in the present instance, an inside flange, a, overlapping the edge of the adjacent box, and the whole being properly secured together by suitable stays or band and bolts, or other appropriate appliances.

Above the fire-grate e, and between the hollow boxes

B' B', is the fire-box X, (shown as removed by fig. 5,) the sides b b of the said box being deeper than the front portion c and the hollow bridge d, the said sides extending down to the grate, as shown by fig. 2; and below the front portion c of the said hollow fire-box is an elongated opening, to which access may be had to the fuel.

At one side of the fire-place, in the hollow box B' of the same, is an opening, provided with a sliding door, g, fuel being introduced through this opening to the fire-place.

In one side of the puddling-chamber is the usual opening, provided with the ordinary sliding door x, adapted to L-shaped strips n n, so fitted to permanent L-shaped guides i i that they can be removed therefrom when a larger door is necessary.

The bed of the furnace is supported by a bridge, E, of cast-iron, beneath which a constant current of fresh air can circulate, thereby preventing that extreme heat which tends to the rapid destruction of the bed of the furnace.

A constant stream of cold water is introduced into the hollow fire-box through a suitable supply-pipe or pipes, the hot water being conducted from the same through appropriate discharge-pipes.

Cold water is also introduced into the hollow boxes B', which form the side plates of the fire-place, and the water passes from box to box, throughout the series which compose the plating of the furnace, through bent connecting-pipes h h; and, with the boxes a short distance above the connecting-tubes h, communicate overflow-pipes i, through which, and through the pipe m, the surplus heated water passes to the cistern L.

In puddling-furnaces of the usual construction the solid plates of the walls, owing to the internal heat to which they are subjected, are apt to become so warped and broken as to be useless, and great expense is incurred in replacing them, while the radiation of heat from the surface of the plates renders the process of puddling, in ordinary furnaces, most oppressive to the operators.

By the employment of hollow boxes in place of the ordinary plates, however, and causing a current of water to pass through these boxes, the exterior of the furnace is maintained at a comparatively low temperature, and the boxes themselves, protected as they are from excessive heat, are prevented from warping or breaking, and the integrity of the brick lining is consequently maintained for a much longer time than walls held by ordinary solid plates.

The communication between the hollow boxes by the exterior bent connecting-pipes h is another advantage of my invention, as they will readily yield to any limited expansion or contraction of the boxes.

The same remarks will apply to the supply-pipes

and discharge-pipes, and all these pipes being of small diameter, but a small quantity of water is consumed in circulating through the boxes.

A further advantage of my invention is the facility with which any one or more of the boxes can be removed, when damaged, and be replaced with a new one, the hollow fire-box X being also detachable.

The boxes being independent of each other in every respect, excepting the above-mentioned pipes, all that is necessary is to disconnect the same when a box has to be removed or replaced.

As another advantage of the furnace, arising from the constant circulation of water around the walls of the same, may be mentioned the reduction in thickness of the usual fire-brick lining, amounting, in many cases, to nearly one-half, and effecting a considerable saving in the first cost of the furnace.

Although I have referred to my invention as applied to a puddling furnace, it will be evident that it may be adapted to heating and other furnaces with the best results.

I do not claim, broadly, a plate supporting the bed

of the furnace so as to allow a current of air to pass beneath the same.

Claims.

1. A series of hollow boxes, B, fitted together and arranged as described, in combination with communicating tubes or channels, so arranged that water introduced into one box will flow through the others successively, as specified.

2. The hollow detachable fire-box X, constructed and adapted to the fire-place, as set forth.

3. The metal bridge E, arched as described, and arranged to support the bed of the furnace.

4. The detachable strips n, adapted to the door x, as set forth.

In testimony whereof I have signed my name to this specification in the presence of two subscribing witnesses.

THOS. E. PURCHASE.
